UNITED STATES PATENT OFFICE.

ALFRED R. MORRILL, OF SWAMPSOFT, MASSACHUSETTS, ASSIGNEE TO UNITED SHOE MACHINERY CORPORATION, OF PATERSON, NEW JERSEY, A CORPORATION OF NEW JERSEY.

SEWING-MACHINE.

1,397,013.

Specification of Letters Patent. Patented Nov. 15, 1921.

Application filed December 18, 1918. Serial No. 267,378.

To all whom it may concern:

Be it known that I, ALFRED R. MORRILL, a citizen of the United States, residing at Swampscott, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

The invention relates to inseam shoe sewing machines such as are used for sewing the uppers to the soles of turn shoes, or the welts and uppers to the insoles of welt shoes.

All features of the invention are applicable to machines in which the stitch forming and work guiding devices are constructed and actuated to impart a continuous feed to the work, during the sewing, and are shown embodied in such a machine, although certain of the features are also applicable to intermittent feed machines.

In accordance with the principal feature of the invention, a small roll is constructed and arranged to act as the channel guide for the shoe, and is so mounted that it may rotate during the relative movement between it and the base of the channel, due to movement of the roll or shoe. In addition to acting as a channel guide, the roll also preferably acts to feed or to assist in feeding the work. In embodying this feature of the invention in a machine in which the feed of the shoe is continuous, the channel guide roll is so actuated that its work engaging surface moves continuously in the direction of the feed, as for instance through rotation, or through bodily movement and rotation of the roll. The roll is preferably mounted in fixed position close to the point at which the needle penetrates the between substance, so that it affords a fixed support about which the shoe may be uniformly and accurately turned in sewing about the toe. This manner of mounting the channel guide roll also enables the stitches to be properly located in sewing about narrow toes, since even in the case of a continuous feed machine there need be comparatively little relative movement in the line of feed between the channel guide and needle. If embodied in a machine in which the feed of the shoe is continuous, the fixed channel guide roll is preferably

continuously driven so that it will tend to continuously advance the work in the line of feed.

The various features of the invention outlined above will be readily understood from an inspection of the accompanying drawings and the following detailed description of the mechanism illustrated therein.

In the drawings, Figure 1 is a view in elevation of the left-hand side of a machine, embodying the various features of the invention; Fig. 2 is a partial front view in elevation, certain parts being removed to more clearly illustrate the parts behind them; Fig. 3 is a sectional detail view looking toward the right in Fig. 2; Fig. 4 is a detail sectional elevation taken substantially on the line 4—4 of Fig. 2, and looking toward the left; and Fig. 5 is a sectional elevation substantially on the line 5—5 of Fig. 4.

In the drawings the invention is shown embodied in a welt and turn sewing machine which is similar in many respects to the machine shown and described in Patents No. 1,076,201, October 21, 1913 and No. 1,108,560, August 25, 1914.

The machine is provided with a curved hook needle 2, a looper 4, a thread arm 6, a back gage 8, which, as shown, also acts as a welt guide, a takeup 10, and an auxiliary takeup 12, all of which are similar in construction to the corresponding parts in the machines of said patents. The machine may also be provided with the usual back rest, which is not shown.

The channel guide is in the form of a small roll 14 adapted to engage the base of the channel. The roll is so mounted that its periphery engages and supports the between substance and that it may rotate during the travel of the shoe with relation to it. The roll not only acts as a channel guide, but also acts to feed or assist in feeding the work, and to that end it is so actuated that its work engaging surface is moved in the direction of the feed while the feed is being effected. In the machine shown the roll is carried on the lower end of a shaft 16 which is mounted in a fixed bearing bracket 18. The roll is thus retained in fixed position close to the needle path and forms a rigid and fixed channel guide which is well adapted for supporting and guiding the shoe and for permitting it to be properly swung in sewing.

about pointed shoes. The roll is actuated to feed or to assist in feeding the work through gear 20 which connects the upper end of the shaft 16 with a worm 22 on the cam shaft of the machine. The gearing may be constructed to rotate the roll continuously or intermittently, as required by the character of the feed which is to be given to the shoe. Since the feed of the shoe is continuous in the machine shown, while the roll is fixed, the gearing is designed to continuously rotate the roll so that its work engaging surface may move continuously in the direction of the feed.

15 In order that the needle and back gage (welt guide) may coöperate with the channel guide roll in effecting or permitting the continuous feed of the work, they are both mounted to reciprocate in the line of feed. 20 The needle is mounted on a slide 24, which is similar in construction to the feed slide of the above patents, and is reciprocated by a cam lever 26 engaging a feed cam 28 on the cam shaft. The needle is secured in a 25 needle segment which is pivotally mounted and guided in a supporting plate 30 projecting down from the slide 24. The needle segment is connected to the actuating lever 32 by a link 34 having ball and socket joints at its connecting ends to permit the movement of the needle segment in the line of feed.

The thread arm 6 is mounted on the supporting plate 30 which carries the needle segment and moves with the needle in the line of feed, so that its relation to the needle is undisturbed, and it is operated through a cam lever and link, as in the machines of the patents referred to.

40 The swinging arm 36, which carries the back gage 8, is mounted on a supporting plate 38 (Fig. 3) secured to a rod 40 mounted to slide lengthwise in bearings in the machine frame, and also forming the supporting stud on which the slide 24 is mounted. The upper end of the arm 36 is supported on a sleeve 42 which is clamped in a bearing in the plate 38. The sleeve surrounds and slides on a fixed stud 44, which also engages 50 an arm on the channel roll bracket 18 (Fig. 2). The arm is connected by a link and ball and socket joints to a back gage slide 46, which is operated and locked at proper intervals by mechanism similar to that of the patents above mentioned. The rod 40 is reciprocated by a cam lever 48, the forward end of which is pivoted to a fixed bracket 50, and the rear end of which carries a roll engaging the feed cam 28. The lever is connected to the rod by a pivot stud 52 (Fig. 3) adjustably secured in a slot in the lever; and engaging a pivot block which fits within a transverse slot in the enlarged end 54 of the rod 40. By adjusting the stud 52, the travel 65 of the back gage in the line of feed may be

varied in accordance with the length of stitch to be sewed, and in accordance with the adjustment of the mechanism which reciprocates the needle.

The timing of the parts is preferably as follows: Assuming that the needle is being retracted, the needle, thread arm, back gage, and the work engaging surface of the channel guide roll are all moving in the direction of the feed, and the channel guide roll is co-operating with the back gage, or with both the back gage and the needle, in feeding the work. After the needle has withdrawn from the work, it is back-fed, while the channel guide roll continues to coöperate with the 75 forwardly moving back gage in continuing the feed of the work. After the back-feed of the needle has been completed, and its forward movement in the direction of feed has begun, it enters the work. As soon as 80 the needle has penetrated the work the back gage is unlocked and is simultaneously moved away from the work and back-fed. During the back-feed of the back gage, the forward feed of the work is continued by the forward 85 travel of the needle and by the rotation of the channel guide. After the back gage has been back-fed and its forward travel begins, it is moved forward against the work and is locked as the needle is about to begin its 90 retracting stroke. This completes the cycle. 95

While it is preferred to employ the specific construction and arrangement of parts shown and described in embodying the invention in a continuous feed machine having 100 the general construction of the machine shown and described in the patents above referred to, it will be understood that this construction and arrangement is not essential to the broader features of the invention, 105 but may be varied or modified as found desirable or best suited to the character of the feed and to the construction and mode of operation of the machine in which it is to be embodied. 110

What is claimed is:—

1. A sewing machine, having, in combination, stitch forming and work guiding mechanism including a needle, a looper, and a channel guide roll having its periphery 115 arranged to engage the between substance at the base of the channel.

2. A sewing machine, having, in combination, stitch forming and work guiding mechanism including a needle, a looper, a channel guide roll, and mechanism for actuating the roll to move its work engaging surface in the direction of the feed. 120

3. A sewing machine, having, in combination, stitch forming and work guiding 125 mechanism including a needle, a looper, a channel guide roll, and mechanism for rotating the roll.

4. A sewing machine, having, in combination, stitch forming and work guiding 130

mechanism including a needle, a looper, a fixed channel guide roll, and mechanism for rotating the roll.

5. A sewing machine, having, in combination, stitch forming and work guiding mechanism including a needle, a looper, a channel guide roll, and mechanism for moving the work engaging surface of the roll continuously in the direction of the feed.

10 6. A sewing machine, having, in combination, stitch forming and work guiding mechanism including a needle, a looper, a back-gage, a fixed channel guide roll, mechanism for continuously rotating the roll, and 15 mechanism for reciprocating the needle and back-gage in the line of feed.

7. A sewing machine, having, in combination, stitch forming and work guiding mechanism including a needle, a back-gage 20 and a channel guide, all mounted to move in the direction of the feed while in engagement with the work, and means for alternately back-feeding the needle and the back-gage.

25 8. A sewing machine, having, in combination, stitch forming and work guiding mechanism including a needle and a back-gage, mechanism for reciprocating them in the line of feed timed to alternately back-

feed them, and a channel guide the work 30 engaging surface of which moves continuously in the direction of the feed.

9. A sewing machine, having, in combination, stitch forming and work guiding mechanism including a needle and a back-gage, mechanism for reciprocating them in 35 the line of feed timed to alternately back-feed them, and a continuously rotating channel guide roll.

10. A sewing machine, having, in combination, two supports mounted to reciprocate in the line of feed, a needle carried on one support, a back-gage carried on the other support, mechanism for reciprocating the supports timed to alternately back-feed 45 them, and a channel guide roll mounted on a fixed support.

11. A sewing machine, having, in combination, two supports mounted to reciprocate in the line of feed, a needle carried on one 50 support, a back-gage carried on the other support, mechanism for reciprocating the supports timed to alternately back-feed them, a channel guide roll mounted on a fixed support, and mechanism for rotating 55 the roll.

ALFRED R. MORRILL.
